DESCRIPTION

FIG. 1 is a top view showing a central fluid-funneling area bounded by a peripheral border;

FIG. 2 is a bottom view;

FIG. 3 is a front view, the rear view being identical;

FIG. 4 is a side view; and,

FIG. 5 is an oblique view depicting a portion of the fluid-funneling area of FIG. 1.

The broken lines in the drawings are for environmental purposes and form no part of the claimed design.
